US00D849874S

(12) **United States Design Patent** (10) **Patent No.:** **US D849,874 S**
(45) **Date of Patent:** **** May 28, 2019**

(54) **MUZZLELOADER PROPELLANT
CARTRIDGE**

(71) Applicant: **Vista Outdoor Operations LLC**,
Anoka, MN (US)

(72) Inventors: **Bryan P. Peterson**, Isanti, MN (US);
David M. Laska, Andover, MN (US);
Matthew S. Schroeder, Princeton, MN
(US); **Adam J. Moser**, Big Lake, MN
(US); **Erik K. Carlson**, Oak Grove,
MN (US)

(73) Assignee: **Vista Outdoor Operations LLC**,
Anoka, MN (US)

(**) Term: **15 Years**

(21) Appl. No.: **29/634,368**

(22) Filed: **Jan. 21, 2018**

(51) **LOC (11) Cl. 22-03**

(52) **U.S. Cl.**

USPC **D22/116**; D22/112

(58) **Field of Classification Search**

Dardi & Herbert PLLC

(57) **CLAIM**

The ornamental design for a muzzleloader propellant cartridge, as shown and described.

DESCRIPTION

FIG. 1 is a perspective view of a muzzleloader propellant cartridge, showing our new design;

FIG. 2 is a perspective view thereof; and,

FIG. 3 is a front side view thereof; the rear side view, the right side view, and the left side view being identical thereto. Subject matter indicated with broken lines forms no part of the claimed design.

1 Claim, 3 Drawing Sheets
